SALES BOOK

Charles Morton Stewart, Jr., Eccleston, Md., assignor to The Baltimore Salesbook Company, Baltimore, Md., a corporation of Maryland

Application April 25, 1940, Serial No. 331,661

1 Claim. (Cl. 282—22)

This invention relates to salesbooks and more particularly to the type known as manifolding salesbooks.

Used by stores of all types for convenience in recording sales, these books are issued to salespeople and usually comprise multiple leaves in manifold sets with insertable interleaved carbon sheets whereby a multiple sales record is made at one writing.

It is the purpose of the present invention to provide a salesbook with means whereby the labeling of packages containing purchases to be sent may be facilitated by having that portion of one of the salesbook leaves which is used as a label for such a package, pregummed.

Referring to the accompanying drawing:

Figure 1 is a perspective view of a triplicate salesbook with a leaf set partly open;

Fig. 2 is a similar view of another form of salesbook;

Figs. 3 and 4 are side elevations with a leaf set open;

Figs. 5 and 6 are perspective views of Figs. 3 and 4;

Figs. 7 and 8 are perspective views of the combined label and delivery record; and

Fig. 9 shows the label in use.

In the salesbook shown in Figures 1, 3, 5 and 7 the numeral 10 indicates the record sheet bound in book form through the medium of a suitable binding 11 and carrying, by means of the usual adhesive spots 12—12 a sheet 13 folded at 14 to form the second, or customer's receipt sheet 15, and the third, or auditor's sheet 16. Below the address box 17 the sheets 15 and 16 are weakened, as at 18, so that the free ends of the sheet 13 may be torn off to leave the short folded portion secured to the sheet 10 by adhesive 12. The short portion is easily detachable from the sheet 10 and is then in the form shown in Fig. 7 wherein part 15' is the remaining portion of sheet 15 and similarly portion 16' is the remaining portion of sheet 16.

Before and during the printing of the various leaves the portion of the sheet 15 directly in rear of the address box 17 is coated with quick drying glue as at 19 and assembled in the finished book. When a package is to be sent the combination shown in Fig. 7 goes to the shipping room along with the merchandise. The bundle

is wrapped, portion 16' separated from portion 15' by tearing along the fold 20, the adhesive coating 19 suitably moistened and the portion 15' affixed to the package by said moistened adhesive to form a delivery label and the portion 16' retained as a shipping label.

In the construction shown in Figures 2, 4, 6 and 8 the address box 17 is at the bottom of the leaves in order to suit the practice of certain stores. In this form the bound in sheet is shown at 21 and is interleaved between upper and lower sheets 22—23 formed by a continuous sheet folded at 24. The sheets 22—23 are weakened at 25 just above the address box 17 in order that the folded central portion may be torn therefrom as in Figure 8. A coating of glue 19 is applied to sheet 23 as shown. This combined label and shipping record is used in the same way as that shown in Figure 7.

20 By forming the salesbook with the pregummed portion underlying the address box 17 thus forming a prepared label much time is saved in the preparation of packages for delivery. The pasting operation usually performed by the shipping clerk is done away with and supplanted by a simple moistening step.

While the invention has been shown as applied to a triplicate record book it may be used in connection with books employing duplicate, triplicate, quadruplicate or other multiple record sets.

What I claim is:

An article of the class described comprising first, second and third leaves in manifold relation, said second and third leaves being detachably connected together at one end and each having a portion detachable from the remainder thereof at a distance from said end, said remainder of the second leaf having adhesive material disposed thereover and being secured by a portion of said adhesive at a restricted area thereof to the third leaf, the structure enabling detachment of said remainders as a unit from the first leaf following detachment of said portions, and subsequent separation of said remainders so that the one provided with adhesive may be used as a delivery label and the other used as a shipping label.
